(57) **CLAIM**

The ornamental design for a combined pickup bumper and trailer hitch, as shown and described.

DESCRIPTION

FIG. 1 is a perspective view of a combined pickup backup bumper and trailer hitch showing our new design;
FIG. 2 is a front elevational view thereof;
FIG. 3 is a rear elevational view thereof;
FIG. 4 is a left side elevational view thereof, the right side elevational view being a mirror image thereof;
FIG. 5 is a top plan view thereof; and,
FIG. 6 is a bottom plan view thereof.
The portions of the vehicle shown in broken lines in FIG. 1 are for illustrative purposes only and form no part of the claimed design.

1 Claim, 3 Drawing Sheets

FIG. 2.

FIG. 3.

FIG. 5.

FIG. 4.
